United States Patent Office.

RICHARD LONG, OF CHILLICOTHE, OHIO.

Letters Patent No. 72,056, dated December 10, 1867.

IMPROVED FURNACES FOR HOT-AIR BLAST.

The Schedule referred to in these Letters Patent and making part of the same.

TO ALL WHOM IT MAY CONCERN:

Be it known that I, RICHARD LONG, of Chillicothe, in the county of Ross, and State of Ohio, have invented a new and improved Furnace Hot-Air Blast; and I do hereby declare that the following is a full, clear, and exact description thereof, which will enable those skilled in the art to make and use the same, reference being had to the accompanying drawings, forming part of this specification.

This invention relates to a new and improved method of constructing and arranging the air-pipe for heating the air-blast for furnaces for smelting and reducing the ores in the manufacture of iron, having particular reference to the materials of which the air-pipe is formed, the method of its construction, and also to the materials and method of construction of the supporting walls; and the invention consists mainly in making the air-pipe of fire-clay, and of an oval form, and in uniting the sections of which the pipe is composed by socket-joints clamped and keyed together, whereby leakage is prevented, and expansion and contraction are provided for, and the apparatus rendered efficient and durable, as will be hereinafter more fully described.

Figure 1 represents an end elevation of the air-pipe supported by suitable walls, with the outside casing removed.

Figure 2 is a horizontal section of the apparatus, showing the columns which support the chimney-stack, and the walls which support the air-pipe, the section being through the line *y y* of fig. 1.

Figure 3 is a vertical sectional elevation, the section being on the line *x x* of fig. 1.

Similar letters of reference indicate corresponding parts.

This apparatus is placed near the furnace-stack, and the heat discharged from the top of the stack in the process of smelting ores is conveyed into this apparatus beneath the air-pipe, passing upwards through and between the sections of the pipe into the chimney which is built upon it and supported by it, so that the blast is heated by the combustible and burning gases which escape from the stack. Utilizing this heat for this and other purposes is by no means new with me. Steam is generated by it for blowing the blast as well as heating it in many establishments.

In arrangements of this kind heretofore used, the heating or blast-pipe and the supporting walls have been made of iron, and being subject to constant expansion and contraction, they soon become cracked and unfit for use. By making the pipe of fire-clay and the supporting walls of fire-brick and plates of metal, I overcome all objections in consequence of expansion and contraction, and render the apparatus durable and not liable to get out of order.

Referring to the drawing, *A* represents the blast-pipe, *B* the supporting walls. *C* represents the main supporting pillars for the chimney, which are of iron. The air-pipe and the supporting walls are enclosed by a casing, marked *D*, which may be either metal or masonry. To the pillars *C*, doors *E* are hinged, to give access to the interior upon each side, as seen in the drawing. As seen, the form of the air-pipe is oval, the advantage of which form is that it affords less surface for ashes to rest upon than a round pipe would. The ashes being a non-conductor, interfere materially with the heating of the blast when resting upon the pipe. The pipe is made in sections, which are united by semicircular pipes or "groove-necks," and the joint, (as seen at *F*, fig. 3,) is a socket-joint, the flanges being united by clamps and keys, as seen in fig. 1 at *g*. The pipe passes and re-passes back and forth in a winding or sinuous form in layers or tiers, connected together by the semicircular pipes, as seen in fig. 1. The interior of the pipe forms a continuous channel for the air, unbroken by any angles or corners. The air enters the lower tier at *h*, and after passing through the pipe is discharged at *J*, from whence it is conducted to near the bottom of the stack in the usual manner. The supporting walls are made of fire-brick, which are fitted to the pipe, each tier of bricks having an iron plate, marked *f*, which separates the tiers or courses of brick, as seen in the drawing. It will thus be seen that all the parts which are exposed to the more intense heat from the flame of the burning gases are constructed of fire-clay and fire-brick, and so arranged that the expansion and contraction by the variations of temperature do not injure or affect them. Beneath the air-pipe *A* there is a plate, marked *H*, which rests on cleats *i i*. When the heater is in operation, an open or perforated plate is employed to check and spread the flame, thereby diffusing it more uniformly under the pipe. In cases of accident or stoppages for temporary repairs outside the heater, a solid plate may be employed to close the space beneath the pipe entirely, for the purpose of retaining the heat and excluding the cold air. On the top

of the apparatus there is another check-plate, G, upon which the chimney rests, the orifice through which is so contracted that the heat is retarded around the pipe, and not allowed to have a free discharge into the chimney, as is usual;

I claim as new, and desire to secure by Letters Patent—

1. Constructing the air-pipe of a furnace-blast heater of fire-clay, substantially as described.
2. Constructing the air-pipe of an oval or other equivalent form, and uniting the sections of which it is composed by socket-joints, with clamps and keys, substantially as shown and described.
3. Forming the supporting walls B of fire-brick, with iron plates between the courses, and substantially as shown and described.
4. Placing an open or solid plate beneath the air-pipe, substantially as and for the purpose herein described.

The above specification of my invention signed by me, this 7th day of October, 1867.

RICHARD LONG.
